UNITED STATES PATENT OFFICE.

HAROLD W. SHONNARD, OF UPPER MONTCLAIR, NEW JERSEY, ASSIGNOR TO CRUCIBLE STEEL COMPANY OF AMERICA, OF PITTSBURGH, PENNSYLVANIA, A CORPORATION OF NEW JERSEY.

LAUNCHING-TUBE.

1,296,335.

Specification of Letters Patent.

Patented Mar. 4, 1919.

Application filed August 30, 1917. Serial No. 188,956.

To all whom it may concern:

Be it known that I, HAROLD W. SHONNARD, residing at Upper Montclair, in the county of Essex and State of New Jersey, a citizen of the United States, have invented or discovered certain new and useful Improvements in Launching-Tubes, of which improvements the following is a specification.

- 10 In my United States Letters Patent No. 1,163,607 I have disclosed mechanism for carrying an electric circuit through the walls of an automobile torpedo and launching tube to an electric motor gyroscope within the torpedo, and for making and breaking such circuit. It is the object of my present invention, which relates to the same general subject matter, to improve the circuit making and controlling mechanism of 15 the launching tube. A more specific object is to provide a launching tube with a single unit for controlling the electric circuit and for unlocking the gyroscope simultaneously with the breaking of the circuit.
- 20 In the accompanying sheets of drawings, which form part of my specification, the preferred embodiment of my invention is illustrated. Figure 1 is a central longitudinal sectional view of the circuit controlling mechanism, and a transverse sectional view of a portion of a launching tube and torpedo therein; Fig. 2 an end view of the circuit controlling mechanism; Fig. 3 a sectional view taken on the line III—III, Fig. 25 1; Fig. 4 a face view of a detail taken on the general plane indicated by the line IV—IV, Fig. 1; Fig. 5 a sectional view taken on the line V—V, Fig. 4; and Fig. 6 a sectional view taken on the line VI—VI, Fig. 5.
- 30 35 In the practice of my invention in its preferred form, a launching tube is provided with an opening through its wall and within this opening there is mounted for reciprocatory movement a circuit controller held 40 45 yieldingly outwardly with respect to the interior of the launching tube. Means are provided for moving such controller inwardly to close a circuit through the wall of a torpedo within the launching tube and to 50 55 hold the controller in this position. Two means are provided to release the controller so that it may move outwardly to break this circuit, one of such means being manually operable, and the other being power con-

trolled, the purpose of the double releasing means being explained hereinafter. Coördinated with the controller and preferably carried thereby, means are provided to move a member, borne by and operable from the exterior of a torpedo, for unlocking the torpedo gyroscope simultaneously with the breaking of the circuit through it.

In the illustrative embodiment of my invention the circuit controller is shown in its adaptation to a launching tube of standard and well known construction, and which has two walls 1 forming between them a chamber for an auxiliary supply of compressed air for launching purposes. Within the tube there is, as shown in Fig. 1, a section of the hull of the torpedo 2 having an opening therethrough closed by means of a plate 3, which plate carries exteriorly exposed electric contactors 4. While but a single contactor appears in the sectional view of Fig. 75 1, it is preferred to provide three contactors for closing a three-phase circuit through the wall of the torpedo.

Within suitable registering openings provided in the side walls 1 of the launching tube, there is placed a tubular casing 5 adapted to be attached to the outer wall of the launching tube as by means of bolts 6, suitable gaskets 7 being provided to prevent the leakage of air from the chamber 80 formed between the walls of the launching tube. A circuit controlling member comprising, in part, a cylinder 8 is mounted for reciprocatory movement within the casing 5. The inner end of the cylinder 8 is provided 85 with a plate 9 in which there are mounted spring-pressed contactors 10 adapted to register with contactors 4 of the torpedo. The contactors 10 are electrically connected to conductors 11 which lead inwardly through 90 the outer end of the casing 5. As will be seen, the plate 9 is provided with a gasket 40 for the purpose of making a water tight connection between such plate and the closure plate 3 of the torpedo.

For the purpose of yieldingly holding the movable circuit controller normally in its outward open-circuit position, there is provided a spring 12, acting between the controller and the casing 5, and to move such controller to its inward closed-circuit position against the resistance of the spring 12, a rack-and-pinion mechanism is preferably

employed. While the spring and rack-and-pinion mechanism may be variously constructed and arranged to carry out the aforementioned ends, the construction shown 5 herein may be advantageously used. To the outer end of the casing 5 there is secured a rack, preferably in the form of a sleeve 13 having rack teeth formed on an extended portion of its curved face. This 10 sleeve, while longitudinally immovable with relation to the casing, is rotatably mounted therein, and is provided with a handle 14 for turning it. Adjacent to the sleeve 13, and preferably in the form of a second 15 sleeve 15 telescoping with the outer face of the first mentioned sleeve, there is a frame attached at its inner end to a transverse plate 16 secured within the cylinder 8; and to this plate 16 there is also attached a rod 20 or bolt 17. One end of the bolt extends within the sleeve 13, and is pressed outwardly (that is to the right as viewed in Fig. 1) by means of the spring 12, which exerts its tension at one end upon a flange 25 or nut 18 at the outer end of the bolt, and at its other end upon a flange 49 formed on the inner end of the rotatable but longitudinally immovable sleeve 13.

The pinion mechanism for engaging the 30 rack face of the sleeve 13 is carried by the sleeve or frame 15, and preferably comprises a rotatable shaft 19 slidably mounted in the outer end of the casing 5, and provided at its outer end with a crank arm 20. At its 35 inner end the shaft is provided with a bevel pinion 21 adapted to mesh with a second pinion 22 secured to a rotatably mounted shaft 23, which shaft in turn has attached thereto a pinion 24 meshing with the rack teeth of 40 sleeve 13. By turning the crank arm 20 in a clockwise direction as viewed in Fig. 2, the pinion 24 will, through pinions 21 and 22 and shaft 23, be turned to cause the frame 15 to move inwardly. This movement of the 45 frame also causes an inward movement of the other parts of the circuit controller, the same including the cylinder 8 and the bolt 17, the spring 12 being compressed, by this movement of the controller, between flange 50 19 of sleeve 13 and the flange or nut 18 at the outer end of the bolt 17.

To hold the circuit controller in its inward position, I preferably provide a 55 spring-pressed latch or pawl 25 pivotally mounted on the frame 15 and adapted to engage a suitable detent 26 formed upon or secured to the side of the rotatable sleeve 13. Thus, when the circuit controller is moved inwardly to its proper position, the latch 25 60 will snap behind the detent 26 and hold the circuit controller in such position, it being understood, as explained above, that the sleeve 13 on which the detent is formed or to which it is attached is longitudinally immovable with respect to the casing 5. To

release the latch 25, the sleeve 13 may be turned by means of the handle 14, it being understood that adjacent to the detent 26 the face of the sleeve 13 is flattened as indicated by the line 27 of Fig. 6. It is for the purpose of permitting such turning of the sleeve 13 that the rack teeth formed thereon are of substantially greater length than the teeth on the pinion 24.

A second and power-operated means for 75 releasing the latch 25 is provided, the same preferably comprising, as shown in Fig. 5, a rod 28, provided with a dog 29 adapted, on the inward movement of the rod, to press against and move the rear end of the latch 80 to release its locking end from the detent 26. The power for thus moving the rod 28 is preferably compressed air led to the casing through a conduit 30, and thence through a central opening 31 formed in the rod 28 85 to a cylinder 32. Within this cylinder the rod is provided with a piston 33 ported to permit the air to flow to the right side thereof as viewed in Fig. 1, so that the rod will be moved inwardly to cause the dog 29 90 to release the latch. The flow of air for thus removing the latch-releasing rod may be controlled in any desired manner, either co-ordinated with or independently of the torpedo-aiming or launching mechanism.

The circuit controller is, in addition to the contactors 10, also provided with a movable member for unlocking the gyroscope within the torpedo. In my co-pending application, Serial No. 188,955, filed of even date herewith, I have disclosed mechanism for unlocking the gyroscope, such mechanism being adapted to be set in operation by pressing inwardly of the torpedo a button extending through the wall thereof. The launching tube mechanism of my present invention is particularly adaptable to move such button, which, in Fig. 1, is indicated at 34. The member borne by the circuit controller for thus unlocking or releasing the 105 gyroscope is preferably a spring-pressed rod 35, mounted for longitudinal movement in the plate 9, and adapted to bear at its outer end against the inner end of the rod 28. By such construction, when the rod 28 is moved 110 inwardly to release the latch, it simultaneously moves the rod 35, which rod in turn presses inwardly the button 34 to unlock the gyroscope in the manner explained in my 115 above-mentioned application.

In the operation of my invention, it being assumed that a torpedo has been placed within the launching tube, the circuit controller is moved inwardly, against the resistance of the spring 12 and to close the circuit through the torpedo contactors 4, by means of the rotation of the crank arm 20. In a manner already explained, the rotation of this arm effects the rotation of the pinion 24 which causes the controller to move in- 120 125 130

wardly and simultaneously compresses the spring 12. When the controller is in the proper position to close the circuit, the latch 25 snaps behind the detent 26 to hold the controller in such position. If, with the parts in this position, it is desirable to test the mechanism to see whether the controller will move rearwardly under the tension of the spring 12, the sleeve 13 may be turned 10 to release the latch 25, it being understood that the outward movement of the controller may thus be effected without moving the gyroscope releasing rod 35. In the outward position of the controller, the operation of 15 the latch and gyroscope releasing rod may be tested by causing compressed air to flow through the tubular rod 28, it being understood that, in such position of the controller, the gyroscope releaser 35 will be beyond the 20 range of engagement of the button 34. When, in actual practice, it is desired to break the circuit through the wall of the torpedo without simultaneously unlocking the gyroscope, the latch may be released in 25 the manner just explained, the gyroscope being subsequently unlocked, as by means of the starting latch shown and described in my above mentioned application.

In the complete operation of the entire 30 mechanism, the controller is first moved inwardly in the manner already described. When it is desired to break the circuit through the torpedo and to simultaneously unlock the gyroscope, air is caused to flow 35 through the pipe 30 and rod 28 to the cylinder 32, where it acts on the right side of the piston 33 to move the rod 28 inwardly. This movement of the rod simultaneously releases the latch 25 and presses inwardly the gyroscope 40 releaser 35, the controller being quickly moved rearwardly under the action of the spring 12. It will be understood, however, that the use of the gyroscope releaser 35 and the coöperating button 34 for unlocking 45 the gyroscope may be dispensed with and the gyroscope unlocked by the launching movement of the torpedo as shown and described in my above-mentioned co-pending application Serial No. 188,955.

50 According to the provisions of the patent statutes, I have described the principle and operation of my invention together with the mechanism which I now consider to represent the best embodiment thereof. However, I desire to have it understood that, within the scope of the appended claims, my invention may be practised by other forms of mechanism than that specifically shown and described herein.

60 I claim as my invention:

1. The combination with a launching tube for automobile torpedoes, of a member movable through the wall thereof and provided with a contactor for closing an electrical circuit through the wall of a torpedo, and

means coördinated with said member for moving a gyroscope lock-controlling member of a torpedo.

2. The combination with a launching tube for automobile torpedoes, of a reciprocatory member in the wall thereof provided with a contactor for closing an electric circuit through the wall of a torpedo, and means carried by said member and movable with relation thereto for moving a gyroscope-controlling member of a torpedo. 70 75

3. The combination with a launching tube for automobile torpedoes, of an electric circuit-controlling member movable through the wall thereof, a spring exerting its tension to hold said member in its outward open-circuit position, and releasable means for holding said member in its inward circuit-closing position. 80

4. The combination with a launching tube for automobile torpedoes, of a circuit-controlling member movable through the wall thereof, a spring exerting its tension to hold said member in its outward open-circuit position, a latch for holding said member in 85 its inward circuit-closing position, and means for releasing said latch. 90

5. The combination with a launching tube for automobile torpedoes, of a circuit controlling member movable through the wall 95 thereof, a spring exerting its tension to hold said member in its outward open-circuit position, a spring-pressed latch for holding said member in its inward circuit-closing position, and two means for releasing said 100 latch, one means being power controlled and the other being manually operable.

6. The combination with a launching tube for automobile torpedoes, of a circuit-controlling member movable through the wall 105 thereof, yielding means acting upon said member to hold it in its outward open-circuit position, and rack-and-pinion connections for moving said member to its inward circuit-closing position against the action of 110 said yielding means.

7. The combination with a launching tube for automobile torpedoes, of a circuit controlling member movable through the wall thereof, a spring exerting its tension to hold said member in its outward open-circuit position, rack-and-pinion connections for moving said member to its inward circuit-closing position, a latch for holding said member in said inward position, and means 115 for releasing said latch. 120

8. The combination with a launching tube provided with an opening through its wall, of a casing secured to said tube and extending into said opening, a circuit controlling 125 member mounted for reciprocatory movement within the casing, a spring exerting its tension to hold said member in outward position, coöperating means borne by said casing and circuit controlling member for 130

- moving the latter to its inward position, and a releasable latch to hold said member in such position.
9. The combination with a launching tube for automobile torpedoes, of a circuit controlling member movable through the wall thereof, yielding means acting upon said member to hold it normally in outward position, a releasable lock for holding said member in its inward position against the action of said yielding means, means borne by said movable member for moving a gyroscope-controlling member of a torpedo, and a single means for releasing said lock and for operating said last-named means.
10. The combination with a launching tube for automobile torpedoes, of a circuit controller movable through the wall thereof and provided on its inner end with a contactor, and a member movably mounted on the inner end of said controller and in its movement adapted to move a gyroscope-controlling member of a torpedo.
11. The combination with a launching tube for automobile torpedoes, of a circuit controller movable through the wall thereof and provided on its inner end with a contactor, yielding means acting upon said controller for holding it normally in its outward position, means for locking said controller in its inward position, a member movably mounted on the inner end of said controller and in its movement adapted to operate a gyroscope-controlling member of a torpedo, and means for simultaneously releasing said locking means and for moving said last named movable member.
12. The combination with a launching tube for automobile torpedoes, of a circuit controller movable through the wall thereof and provided with a contactor adapted to close a circuit through the wall of a torpedo, yielding means acting upon said controller for holding it normally in its outward open-circuit position, means for locking said controller in its inward position, a gyroscope releaser movably mounted on said controller, means for simultaneously releasing said locking means and for moving said gyroscope
- releaser, and means for releasing said locking means independently of the movement of said gyroscope releaser.
13. The combination with a launching tube for automobile torpedoes provided with an opening through its wall, a tubular casing borne by said tube within said opening, a rack secured to the outer end of and projecting within said casing, a circuit controller mounted for reciprocation within said casing, a pinion drive mechanism secured to said controller and engaging said rack, yielding means acting upon said controller to hold it normally in outward position, and a releasable means for holding the controller in its inward position.
14. The combination with a launching tube for automobile torpedoes provided with an opening through its wall, a tubular casing borne by said tube within said opening, a cylindrical rack rotatably mounted in and projecting into said casing, said rack being provided with a latch-engaging detent, a circuit controller mounted for reciprocation within said casing, a pinion drive mechanism secured to said controller and engaging said rack, yielding means acting upon said controller to hold it normally in outward position, and a latch secured to said controller and adapted to engage the detent formed on said rack to hold the controller in its inward position, said latch being adapted to be released from said detent by the rotation of said rack.
15. The combination with a launching tube for automobile torpedoes provided with an opening through its wall, a circuit controller movable through said opening and provided with a contactor, a reciprocatory gyroscope releaser carried by said controller, and pneumatically operated means for moving said releaser.

In testimony whereof I have hereunto set my hand.

HAROLD W. SHONNARD.
